NEEDLE PACKAGE

Courtland H. Barr, Sr., Los Angeles, Courtland H. Barr, Jr., La Canada, and John W. Barr, Glendale, Calif., assignors to Courtland Laboratories, Los Angeles, Calif., a corporation of California

Filed Dec. 30, 1966, Ser. No. 606,347
9 Claims. (Cl. 206—17)

This invention relates to a novel package for a cannula, and to the packaged cannula which is particularly adapted for sale and use with modern cannula holders.

Various cannula packaging devices have been proposed. In general, an acceptable cannula package must provide for the maintenance of the sterility of the cannula during shipment and storage. In addition, the cannula package must be capable of holding the cannula in such a way that the sharpened ends of the cannula do not become dulled or burred during transit and storage. In addition, it is necessary that the cannula package be of simple inexpensive design and materials of construction since normally the cannula packages are not adapted for reuse.

Accordingly, the present invention is primarily concerned with a novel package for cannulae, and more particularly is concerned with a novel package for cannulae having two sharpened ends and an intermediate obtuse portion which cannula package is particularly adapted for use with modern type cannula holders.

Thus, it is a principal object of the present invention to provide a novel package for a cannula.

More particularly, it is an object of the present invention to provide a novel package for a cannula having two straight end portions connected by an intermediate obtuse portion which is particularly adapted for sale and use with modern cannula holders.

Specifically, it is an object of the present invention to provide a novel package for a cannula having two straight end portions connected by an intermediate obtuse portion wherein there is an outer cover member and an inner slide member which is slidably received in drawer-like fashion in the cover portion and adapted to hold the cannula, the slide member having a reduced lateral cross-section at a point along its length to facilitate the breaking away of a portion of the slide when partially withdrawn from the cover to thereby expose a portion of the cannula for reception by the cannula holder.

These and other objects and advantages of the present invention will become more apparent from the detailed description which follows, taken in conjunction with the accompanying drawings in which:

FIGURE 1 is a top plan view of the novel cannula package of the present invention.

FIGURE 2 is a sectional view taken along the line 2—2 in FIGURE 1.

FIGURE 3 is a sectional view taken along the line 3—3 of FIGURE 2.

FIGURE 4 is a plan view of the cannula packaged in the novel cannula package of the present invention.

FIGURE 5 is a perspective view of the novel cannula package of the present invention containing the cannula wherein the slide member has been broken away at the point of reduced lateral cross-section to expose one straight end portion and the intermediate obtuse portion of the cannula.

Briefly, the present invention comprises a novel package for a cannula having two straight end portions connected by intermediate obtuse portion comprising an outer cover member and an inner slide member which is slidably received in the cover portion and adapted to hold the cannula, said slide member being of reduced lateral cross-section at a point along its length to facilitate the breaking

2

away of a part thereof when partially withdrawn from the cover. The present invention additionally comprises the novel cannula package above-described wherein the cannula is received in a depressed recess in the slide member and snugly slidably gripped therein by retaining means for one end of the cannula comprising a plurality of dowels and the side of the recess.

Turning to the drawings in greater detail, the outer cover member is indicated generally as 10 and the slide member is indicated as 12. The slide member 12 is slidably receivable within the cover member 10. The slide member 12 has a depressed recess 14 therein in which is received cannula 16 having two straight end portions 18 and 20 and intermediate obtuse portion 22 connecting said straight portions. At point 24 along the length of slide member 12, there is provided a section of reduced cross-section to facilitate the breaking away of the one portion of the slide member 12 in the manner shown in FIGURE 5. In this way, the straight end portion 18 and the intermediate obtuse portion 22 of the cannula may be exposed for reception in a cannula holder. When the cannula is in the position shown in FIGURE 5, it is particularly adapted for reception in the cannula holder described in assignee's copending U.S. Patent application, Ser. No. 560,040, the disclosure of which is expressly incorporated herein by reference.

The dowels 26 and 28 in recess 14 cooperate with the sides of the recess to hold end portion 20 of the cannula. The spacing between the two dowels and the sides of the recess is such that the cannula is snugly gripped therebetween, but permits the cannula to be slid therefrom after the straight portion 18 and the intermediate obtuse portion 22 have been inserted in the cannula holder. The T-portion 30 shown in FIGURE 1 is raised to a height approximately equal to or greater than the diameter of the cannula, and one branch of the T is adapted to abut the intermediate obtuse portion of the cannula to prevent the cannula from being shaken loose from the grip provided between the sides of the recess and the two dowels. The undersides of the cover 10 and slide 12 are provided with cooperating stop means so that the inner slide member 12 can be withdrawn from the cover 10 only to the extent necessary to expose the area of the slide having the reduced lateral cross-section. This prevents the accidental complete withdrawal of the slide member which is undesirable as will be more fully hereinafter explained. The stop means comprises small projections 32 on the underside of the slide 12 which cooperate with projections 34 on the underside of the cover 10. The projections 32 and 34 are positioned so that when they are in contact, the area of the reduced cross-section of the slide 12 is just protruding from the end of the cover member 10 as shown in FIGURE 5. In this way, the exposed portion of the slide can be readily broken away.

As can be seen, the present invention provides a cannula package designed to permit only the exact withdrawal of the portion containing one straight end portion and the obtuse portion of a cannula from the portion acting as the protective cover. The fitting of the cover 10 and the slide 12 allows for ready assembly of the two components but prevents inadvertent disassembly when withdrawing the inner slide member 12 from the cover 10. The stop-motion design is in such relationship to the juncture of the two straight end portions of the cannula so as to allow sufficient exposure of the obtuse portion to properly engage into the cannula holder permitting the clamping means of the needle holder to effectively engage. The part of the cannula still covered as shown in FIGURE 5 is the portion which will later be inserted into the vein of a patient. For this reason it

necessary that this portion remain covered until it is ready for use.

The stop means also plays another role. At the time the cannula is to be exposed for use, the stop means between the slide member 12 and the cover 10 is such that the grip is greater than the grip of the dowels 26 and 8 and side of the recess against the cannula. Thus, when proper force is exerted after straight end portion 8 and intermediate obtuse portion 22 have been secured to the cannula holder, the cannula portion 20 becomes removable from the slide member.

It will be understood that many variations are possible in the present invention. For example, the various lowels and supporting members required to maintain the cannula in the desired position with respect to the slide 12 may be widely varied. Any form of dowel, raised members, and the like may be utilized so long as the cannula is maintained in a position whereby one portion of the slide member may be broken away to expose a straight portion and an intermediate obtuse portion of the cannula and at the same time provide for shipment of the cannula without damage thereto or impairment of its sterility. The novel package of this invention can be made of any of the common materials of construction including metal and plastic. Typically, the package, or at least the cover 10 thereof, is made of a transparent plastic, as depicted in the drawings.

Thus, all such modifications and variations of the present invention are intended, and the invention is to be limited only by the lawful scope of the appended claims.

We claim:

1. A novel package for enclosing a cannula having two sharpened ends and two straight end portions connected by an intermediate obtuse portion comprising an outer cover member and an inner slide member which is slidably received in said cover member and having a recess therein, said recess also having a plurality of dowels therein to form with the side of said recess, a retaining means to snugly slidably grip one straight end of said cannula, said slide member being of reduced lateral cross-section at one point along its length to facilitate the breaking away of a part of said slide member when it is partially withdrawn from said cover.

2. A novel package for enclosing a cannula having two sharpened ends and two straight end portions connected by an intermediate obtuse portion comprising an outer cover member and an inner slide member which is slidably received in said cover member and having a recess therein, said slide member comprising two portions connected by a section of reduced lateral cross-section, the recess in one of said portions being of sufficient length to accommodate one straight portion of the cannula and the recess in the other portion being of sufficient length to accommodate the longitudinal length of one straight end portion and the intermediate obtuse portion of the cannula, said recess in said one portion having a plurality of dowels therein to form with the side of said recess, a retaining means to snugly slidably grip one straight end portion of said cannula, said section of reduced lateral cross-section facilitating the breaking away of said other portion of the slide member when said slide member is partially withdrawn from said cover to thereby expose one straight end portion and the intermediate obtuse portion of the cannula.

3. A novel package for enclosing a cannula having two sharpened ends and two straight end portions connected by an intermediate obtuse portion comprising an outer cover member and an inner slide member which is slidably received in said cover member and having a recess therein, said slide member comprising two portions connected by a section of reduced lateral cross-section, the recess in one of said portions being of sufficient length to accommodate one straight portion of the cannula and the recess in the other portion being of sufficient length to accommodate the longitudinal length of one straight end

portion and the intermediate obtuse portion of the cannula, said recess in said one portion having a plurality of dowels therein to form with the side of said recess, a retaining means to snugly slidably grip one straight end portion of said cannula, said section of reduced lateral cross-section facilitating the breaking away of said other portion of the slide member when said slide member is partially withdrawn from said cover to thereby expose one end straight portion and the intermediate obtuse portion of the cannula, said cover and inner slide member having cooperating stop means on the undersides thereof so that said inner slide member can be withdrawn from the cover only to the extent necessary to expose the area of the slide member having the reduced lateral cross-section.

4. A novel package for enclosing a cannula having two sharpened ends and two straight end portions connected by an intermediate obtuse portion comprising an outer cover member and an inner slide member which is slidably received in said cover member and having a recess therein, said slide member comprising two portions connected by a section of reduced lateral cross-section, the recess in one of said portions being of sufficient length to accommodate one straight portion of the cannula and the recess in the other portion being of sufficient length to accommodate the longitudinal length of one straight end portion and the intermediate obtuse portion of the cannula, said recess in said one portion having a plurality of dowels therein to form with the side of said recess, a retaining means to snugly slidably grip one straight end portion of said cannula, said recess in said other portion having means for abutting said cannula to prevent relative movement between said cannula and said slide when the slide is received in said cover, said section of reduced lateral cross-section facilitating the breaking away of said other portion of the slide member when said slide member is partially withdrawn from said cover to thereby expose one end straight portion and the intermediate obtuse portion of the cannula, said cover and inner slide member having cooperating stop means on the undersides thereof so that said inner slide member can be withdrawn from the cover only to the extent necessary to expose the area of the slide member having the reduced lateral cross-section.

5. A novel cannula package comprising an outer cover member and an inner slide member which is slidably received in said cover portion, received in said slide member a cannula having two straight end portions connected by an intermediate obtuse portion, said slide member being of reduced lateral cross-section at a point along its length to facilitate the breaking away of a part of said slide member when partially withdrawn from said cover and thereby expose a portion of the cannula.

6. A novel cannula package comprising an outer cover member and an inner slide member which is slidably received in said cover member, said slide portion having a recess, received in said recess a cannula having two sharpened ends and two straight end portions connected by an intermediate obtuse portion, said slide member being of reduced lateral cross-section at a point along its length to facilitate the breaking away of a part of said slide member when it is partially withdrawn from said cover.

7. A novel cannula package comprising an outer cover member and an inner slide member which is slidably received in said cover member and having a recess therein, received in said recess a cannula having two sharpened ends and two straight end portions connected by an intermediate obtuse portion, said slide portion also having a plurality of dowels therein to form with the side of said recess, a retaining means snugly slidably gripping one end of said cannula, said slide member being of reduced lateral cross-section at one point along its length to facilitate the breaking away of a part of said slide member when it is partially withdrawn from said cover.

8. A novel cannula package comprising an outer cover member and an inner slide member which is slidably received in said cover member and having a recess therein, received in said recess a cannula having two sharpened ends and two straight end portions connected by an intermediate obtuse portion, said slide member comprising two portions connected by a section of reduced lateral cross-section, the recess in one of said portions being of sufficient length to accommodate one straight portion of the cannula and the recess in the other portion being of sufficient length to accommodate the longitudinal length of one straight end portion and the intermediate obtuse portion of the cannula, said recess in said one portion having a plurality of dowels therein to form with the side of said recess, a retaining means snugly slidably gripping one straight end portion of said cannula, said section of reduced lateral cross-section facilitating the breaking away of said other portion of the slide member when said slide member is partially withdrawn from said cover to thereby expose one straight end portion and the intermediate obtuse portion of the cannula.

9. A novel cannula package comprising an outer cover member and an inner slide member which is slidably received in said cover member and having a recess therein, received in said recess a cannula having two sharpened ends and two straight end portions connected by an intermediate obtuse portion, said slide member comprising two portions connected by a section of reduced lateral

cross-section, the recess in one of said portions being of sufficient length to accommodate one straight portion of the cannula and the recess in the other portion being of sufficient length to accommodate the longitudinal length of one straight end portion and the intermediate obtuse portion of the cannula, said recess in said one portion having a plurality of dowels therein to form with the side of said recess, a retaining means snugly slidably gripping one straight end portion of said cannula, said section of reduced lateral cross-section facilitating the breaking away of said other portion of the slide member when said slide member is partially withdrawn from said cover to thereby expose one straight end portion and the intermediate obtuse portion of the cannula, said cover and inner slide member having cooperating stop means on the undersides thereof so that said inner slide member can be withdrawn from the cover only to the extent necessary to expose the area of the slide member having the reduced lateral cross-section.
